PLASTIC SHOE

Ruth Rosen, Chicago, Ill.

Application May 12, 1958, Serial No. 734,593

2 Claims. (Cl. 36—7.1)

This invention relates to overshoes for protection against rain or snow, and more particularly this application relates to an overshoe which may be conveniently folded away when not in use, so that it may be carried in a user's pocket or purse.

Heretofore, the great majority of overshoes have been constructed so that they are very heavy in weight and bulky, and walking in them has been awkward. More recently, there has been a trend toward plastic overshoes, and, while these overshoes are somewhat lighter in weight, nevertheless, they are still sufficiently bulky that they can not be easily folded for storage in women's purses, and the like. With respect to the plastic type overshoes, these are generally molded with a predetermined sole shape to correspond with existing sole shapes. With respect to overshoes worn by women, those overshoes that are molded with a flat sole shape are not attractive enough to be used for dress wear and, consequently, women generally have to buy more than one pair of overshoes for use with shoes of different heel shapes and sizes.

One of the objects of this invention is to provide a new and improved overshoe which is so constructed and arranged that it may easily be folded for storage in the purse or in the pocket of its user.

Another object of this invention is to provide an overshoe construction wherein the sole thereof normally tends toward folding along a longitudinal medial axis thereof so that the overshoe normally folds flat, in a convenient form for folding and storage thereof.

A further object of this invention is to provide an overshoe construction wherein the sole portion thereof is sufficiently flexible so that it may be caused to accommodate itself to shoes of varying heel shape and size, so that a single pair of overshoes may be used for either regular or dress wear.

Still another object of this invention is to provide a simple and inexpensive overshoe construction which is extremely light in weight, and which is characterized by its efficiency in use and by its attractiveness in appearance.

Further objects and advantages of this invention will become apparent as the following description proceeds and the features of novelty which characterize this invention will be pointed out with particularity in the claims annexed to and forming part of this specification.

A preferred embodiment of the invention is shown in the accompanying drawings, in which:

Figure 1 is a perspective view of an overshoe constructed in accordance with this invention.

Figure 2 is a perspective view showing the overshoe of Figure 1 enveloping a woman's high-heeled shoe.

Figure 3 is an enlarged side elevation view of the overshoe showing its appearance when folded flat.

Figure 4 is a cross-section view taken substantially on line 4—4 of Figure 3.

Figure 5 is an enlarged fragmentary cross-section view taken substantially on line 5—5 of Figure 3.

2

Referring now to the drawings, there is shown an overshoe 10 which has an integrally formed body that is adapted to be folded to a flat condition when not in use, as best seen in Figures 3—5, and which may be opened up to an operative shoe-receiving condition, as best seen in Figures 1 and 2. When the overshoe 10 is folded flat, then there is defined a pair of similarly shaped, upright, overshoe-side portions 12 and 14 whose general outline appears as in Figure 3, and which generally defines, at 10 the lower end, a laterally elongated, sole-edge portion 16, an inclined vamp portion 18, and an ankle portion 20 disposed laterally adjacent the vamp portion 18, and a leg-receiving portion 22 at the upper end. The vamp portion 18 and the ankle portion 20 are disposed laterally 15 of each other, and are, in aggregate of a smaller lateral dimension than the sole-edge portion 16. It will be seen that said vamp portion 18 and ankle portion 20 of the overshoe are disposed between the lower sole-edge portion 16 and the upper leg-receiving portion 22. The leg-receiving portion 22 is of still smaller lateral dimension than the other portions of the overshoe, and terminates at the upper edge 24. The pair of similarly shaped, upright side portions 12 and 14, merge at the lateral, upright fold edges 26 and 28 to define a generally tubular body portion whose upper end constitutes an open mouth through which a shoe may be introduced into the overshoe.

The bottom of the tubular body of the overshoe is closed off by a bottom member 30 which merges at its 30 peripheral edges with the edges of said tubular body. The bottom 30 is preformed and preshaped of a flexible material so that it normally folds longitudinally upon itself upwardly, along its longitudinal medial axis line 32, and the folded bottom is then arranged to be tucked between the pair of overshoe-side portions 12 and 14, in the manner as best seen in Figure 5, so that the entire overshoe is normally in generally flat condition when not in use.

The bottom 30 of the overshoe is adapted to spread out flat, to a condition as seen in Figures 1 and 2, so as to open or enlarge the lower end of the overshoe 10, upon a shoe S being entered into the overshoe and being thrust against the inner surfaces of the overshoe bottom 30.

In the preferred form, the sides 12 and 14 of the overshoe are formed integrally with the bottom 30, and preferably the bottom 30 is of a greater thickness than the thickness of the side portions 12 and 14. One of the reasons for increasing the bottom 30 is that this portion 45 is subjected to the greatest wear, and, secondly, the greater thickness of the bottom 30, in combination with the preformed shape which normally tends toward the folded condition, as seen in Figure 5, operates to normally effect a collapsing of the overshoe to the flat, folded condition, as seen in Figures 3—5. The side portions 12 and 14 of the overshoe are preferably of very thin 55 flexible material and it will be readily evident that the flat shoe thus described may be easily folded still further or rolled up into a convenient package for storage in the purse or pocket of the user.

The overshoe thus described is normally formed of a size and outline to accommodate shoes of a large variety of sizes and shapes and, hence, is not designed to closely hug the contour of a shoe or of a foot. In order to effect 65 a close hugging of the overshoe to the foot of a wearer, and to provide an attractive appearance, there is provided a first flexible gripping means generally indicated at 34, which is secured to the inclined vamp portion of the tubular body portion and which is of a length to reach under 70 and around the bottom of the overshoe at a region below the arch of a shoe S positioned within the overshoe. As best shown in Figure 2, the flexible gripping means en-

gages the underside of the bottom 30 of the overshoe at a point between the heel and the ball portion of the sole of the shoe, and the flexibility of the bottom 30 of the overshoe 10 permits the shaping of the overshoe by the gripping means 34 as seen in Figure 2, so as to cause the overshoe to accommodate itself to shoes of varying shape, size, and height of heel. More specifically, the first flexible gripping means 34 includes an elongated flexible tie member 36 which is secured intermediate its ends, by means of heat-sealing or the like, or by means of a patch 37 to the inclined vamp portion 18 of the overshoe, and the free ends of the elongated, ribbon-like tie member 36 are adapted to be tied in an attractive bow, as illustrated at 38 in Figure 2, which bow is disposed on the outside of the shoe so as to enhance the appearance thereof.

A second flexible gripping means is secured to the leg-receiving portion 22 of the overshoe 10 above the ankle portion thereof, and is adapted to effect a constricting of the open mouth portion of the overshoe to cause said mouth portion of the overshoe to lie snugly against and hug a leg therein. More specifically, the outer side 12 of the overshoe 10 has therein a slit 40 extending from adjacent the region of the ankle portion 20 of the overshoe upwardly to the edge 24 which defines the open mouth of the tubular body of the overshoe. Disposed on opposite sides of the slit 40 are a pair of spaced, flexible, ribbon-like tie segments 42 and 44 which are secured by heat-sealing or the like, or by means of tabs 46, to the overshoe. The tie segments 42 and 44 are adapted to be tied together so as to effect a constricting of the sides of the open mouth of the tubular body of the overshoe, and when so tied they yield an attractive bow 48 disposed on the outside of the overshoe, as best seen in Figure 2.

It is to be understood that, while the overshoe 10 of this invention is, in its preferred form, formed of a transparent plastic material, the overshoe could equally well be formed of a cloth material or soft leather or rubber type material, and the bottom 30 of the overshoe should be formed of any material which will tend toward retaining its normally folded position, as shown in Figure 5, but which is resilient enough to be spread to a shoe-approximating shape as seen in Figure 2.

The tie members 36, 42 and 44, while preferably formed of a plastic material which may be heat-sealed to an overshoe formed of plastic, may also be formed of bright-colored cloths, or other flexible materials, so as to enhance the appearance of the overshoe.

It will be seen that the construction of the overshoe 10 is such that a user, by lightly pulling upon the heel and toe will cause the bottom 30 to fold into place as in Figures 3-5, and thereafter the shoe may be folded further or rolled up for storage. The tie means 36 may be preformed as a continuous stretchable member, and in any event operates to cause the greater portion of the overshoe to fit snugly against the foot of the wearer. While the overshoe is shown slitted on one side, it will be understood that the overshoe may alternatively be open at the front or back and may even be closed all around. Although tie elements 42 and 44 are preferable, the overshoe could also use zippers, snaps, or hooks and eyes to effect the constricting of the open mouth portion of the overshoe.

While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What I claim as new, and desire to secure by Letters Patent of the United States, is:

1. An overshoe comprising an integrally formed flexible overshoe body formed of a transparent plastic and defining a pair of similarly shaped upright side portions whose outline generally defines a laterally elongated sole-

edge portion at the lower end, an inclined vamp portion and laterally adjacent ankle portion, of smaller lateral dimension, above said sole-edge portion, and a leg-receiving portion of still smaller lateral dimension at the upper end; the upright peripheral edges of said pair of side portions merging to define a flexible tubular body portion whose upper end constitutes an open mouth through which a shoe may be introduced into the overshoe, and the leg-receiving portion of one of said pair of side portions being slitted from adjacent the ankle portion thereof upwardly to the edge defining the open mouth of the overshoe; an elongated flexible overshoe bottom closing off the lower end of said flexible tubular body portion and merging with the lower peripheral edges of said pair of side portions, the bottom of said overshoe and its connection with the lower peripheral edges of said pair of side portions being preformed to cause said bottom to normally fold back on itself and to fold upwardly between said pair of side portions, so that the normally folded bottom operates to normally effect folding of the flexible overshoe toward a generally flat condition, said bottom of the overshoe adapted to spread out flat to open the flexible lower end of the overshoe upon a shoe being entered into the overshoe and being thrust against the inner surfaces of said overshoe bottom, said sides and bottom of the overshoe being formed integrally and of the same material and with said bottom being of a material thickness greater than the thickness of the said side portions, and a first elongated tie member secured intermediate its ends to the inclined vamp portion of the tubular body portion and providing free ends which may be conveniently tied together and which are of a length to reach under and around the flexible body of the overshoe, at a region below the heel and ball portion of the sole of a shoe within the overshoe, a pair of second tie members secured to the slitted leg-receiving portion of the overshoe on opposite sides of the slit therein, said tie members adapted to be selectively tied together to effect a constricting of the flexible open mouth portion of the overshoe to cause said mouth portion of the overshoe to lie snugly against a leg therein, and said first tie member and said pair of second tie members cooperating to cause said overshoe to assume a contour approximating the shape of the shoe and leg therein so as to present an attractive appearance.

2. An overshoe comprising an integrally formed flexible overshoe body defining a pair of similarly shaped upright side portions whose outline generally defines a laterally elongated sole-edge portion at the lower end, an inclined vamp portion and laterally adjacent ankle portion, of smaller lateral dimension, above said sole-edge portion, and a leg-receiving portion of still smaller lateral dimension at the upper end; the upright peripheral edges of said pair of side portions merging to define a flexible tubular body portion whose upper end constitutes an open mouth through which a shoe may be introduced into the overshoe, and the leg-receiving portion of one of said pair of side portions being slitted from adjacent the ankle portion thereof upwardly to the edge defining the open mouth of the overshoe; an elongated, flexible, planar overshoe bottom closing off the lower end of said tubular body portion and merging with the lower peripheral edges of said pair of side portions; a first elongated tie member secured intermediate its ends to the inclined vamp portion of the tubular body portion and providing free ends which may be conveniently tied together and which are of a length to reach under and around the outside of the bottom of the overshoe, at a region below the shank of a shoe positioned therewithin, a pair of second tie members secured to the slitted leg-receiving portion of the overshoe on opposite sides of the slit therein, said tie members adapted to be selectively tied together to effect a constricting of the open mouth portion of the overshoe to cause said mouth portion of the overshoe to lie snugly against a leg therein, said first tie member and pair of second tie members cooperating to cause said

flexible overshoe and its flexible, planar bottom to assume a contour approximately the shape of the shoe and leg therein so as to present an attractive appearance, and said first tie member and said pair of second tie members being arranged and positioned to be tied adjacent the outer side of the overshoe, so that the ties appear as ornamentation for the overshoe.
